Application April 29, 1949, Serial No. 90,484

14 Claims. (Cl. 122—459)

1

This invention relates to vapor generators and more particularly pertains to steam generators and to a method of and means for generating steam.

It has been determined that fouling of the blades of a turbine can be caused by very pure steam from the steam generator, that is, by steam containing a fraction of one part per million total solids as determined by the conductance method. Certain chemical constituents of boiler water, such as silica, the presence of which is not revealed by the conductance test, escapes from the boiler water into the steam in vapor form and, at high pressure, hydroxides, chlorides, sulphates, etc. are dissolved by the steam. In high pressure boilers particularly, silica is vaporized in the steam drum, entrained in said steam and passed in vapor form from the drum in admixture with the steam. The silica, because it is vaporized, is not removed by drying of the steam and passes to the turbine where it condenses on the turbine blades in the low pressure, low temperature stages thereof causing a marked reduction in the capacity of the turbine. The amount of silica vaporized in the boiler increases with the pressure, the saturation temperature, and the concentration of the boiler water from which the steam is released, and decreases as the pH increases. It is necessary, therefore, in order to maintain turbine capacity that only steam from which dissolved or vaporized solutes have been removed be passed to the turbine. Also, it is highly desirable that any scale formations caused by impurities from the feed water of a steam generator be confined substantially to tubes which are exposed only to relatively low temperature heating gases.

In accordance with the present invention, steam which is substantially free of dissolved or vaporized solutes is passed from a vapor generator and scale formations from impurities in the feed water of the steam generator are confined substantially to those tubes exposed only to relatively low temperature heating gases.

The invention has special application to high pressure, high temperature steam generators which are required to operate with feed water of high initial solid concentration, due to the necessity of using high percentages of make-up water. However, the invention is capable of application to steam generators generally.

In accordance with the present invention, pure steam, that is, steam free of dissolved or vaporized solutes, is produced and concentration of dissolved solids in the boiler water of the steam

2

generator is controlled by arranging the heating surface of the generator in two or more separate heat absorbing sections, each of which has its own independent circulation system. The feed water enters a primary high duty heat absorbing section which is continuously blown down to a low duty secondary section. The secondary section is subjected to relatively low rates of heat absorption by convection. The continuous blowdown from the primary section is large compared to the steam output of the entire steam generating unit. A low boiler water concentration is maintained in the primary highly heated furnace tubes, while a much higher concentration is maintained in the moderately heated tubes of the secondary section. The possibility of damage to the tubes in the primary or radiant heating absorbing section which operates at high heat transfer rates is minimized because in these tubes a low concentration is maintained, while in the secondary (convection) section, which is subjected to low rates of heat transfer and low temperatures, high concentrations can be tolerated. Also, since the concentration in the primary section where the major portion of the steam is generated is low in accordance with the present invention, the amount of silica or other solute vaporized is low. The steam released in the secondary section, which steam is made from the highly concentrated boiler water, will have a greater solute concentration but the steam generated in the secondary section is relatively small compared to the total boiler output. In accordance with the present invention, this relatively small amount of vaporized solute in steam from the secondary section is eliminated. Subcooling of the downcomers of the steam generator of the present invention is also prevented by washing the steam generated in the primary section in a portion of the feed water as the steam is treated in vapor and liquid separators thereby heating the feed water to saturation prior to the feed water entering the downcomers and by condensing steam from the secondary section by direct heat exchange relationship with the remaining portion of the feed water.

The particular features and advantages which characterize the invention will be understood from the following description when considered in connection with the accompanying drawings forming a part thereof and in which:

Fig. 1 is a vertical sectional view illustrating more or less diagrammatically, a steam generator embodying the invention;

Fig. 2 is a vertical sectional view taken on the line 2—2 of Fig. 1;

Fig. 3 is a view similar to Fig. 2 but taken on the line 3—3 of Fig. 1;

Fig. 4 is an enlarged transverse sectional view taken on the line 4—4 of Fig. 2;

Fig. 5 is a longitudinal sectional view taken on the line 5—5 of Fig. 4;

Fig. 6 is an enlarged transverse sectional view taken on the line 6—6 of Fig. 4;

Fig. 7 is an enlarged fragmentary sectional view of the upper part of Fig. 4;

Fig. 8 is a view similar to Fig. 6 but taken on the line 8—8 of Fig. 4;

Fig. 9 is a view similar to Fig. 8 but of another embodiment of the invention;

Fig. 10 is a perspective view of the steam and water drum of the primary section of the present invention with parts thereof broken away, and

Fig. 11 is a chart showing a group of curves which illustrate graphically operating characteristics of the steam generator of the present invention.

Like characters of reference refer to the same or similar parts throughout the several views.

Referring to the drawings, Figs. 1—3, the steam generator of the present invention comprises a setting 10 having therein a combustion chamber 11 with a front wall 12, a rear wall 13 and opposite side walls 14 and 15. The front wall 12 is inclined inwardly at the opposite ends thereof to form a roof portion 16 at the top thereof and a bottom portion 17 at the bottom thereof. Rear wall 13 is inclined inwardly at the top thereof toward chamber 11 at an elevation lower than side wall 12 to thereby form another roof portion 18 which roof portion extends upwardly to a point short of roof 16 thereby forming a gas outlet 19 at the top and rear of chamber 11. Wall 13, like wall 12, has an inclined bottom 20, the bottom portions 17 and 20 of front and rear walls 12 and 13 respectively thereby forming a hopper bottom to chamber 11.

The primary high duty heat absorbing section of the vapor generator of the present invention comprises an upper steam and water drum 21 disposed above roof portion 16 which drum has water wall riser connecting tubes 22 in communication therewith and extending downwardly to connect with header 23. Opposite side walls 14 and 15 are lined respectively with water wall tubes 24 and 25. The tubes 24 communicate at the top thereof with header 23, while the tubes 25 are in communication at the upper end thereof with a header 26 similar to header 23. Riser tubes 27 are connected with header 26 and drum 21, as shown in Fig. 2. Front wall 12, including roof 16 and bottom portion 17, is lined with water wall riser tubes 28, while rearward wall 13, including roof portion 18 and bottom 20, is lined with water wall riser tubes 29, the tubes 29 extending across outlet 19 at the top thereof and communicating with drum 21. The lower end of tubes 28 and 29 communicates respectively with headers 30 and 31 adjacent the bottom of portions 17 and 20. A plurality of downcomer tubes 32 are connected at one end thereof with the lowermost portion of drum 21 and at the opposite end thereof with downcomer header 33. Main downcomer conduits 34 and 34' (Figs. 2 and 3), adjacent the outer side of side walls 14 and 15 respectively, connect at the top thereof with header 33 and extend downwardly to a point below and centrally of bottom portions 17 and 20, as shown in Fig. 1. Downcomer conduits 34 and 34' are in communication at the lower end thereof

with header 30 through tubes 35 and with some of riser tubes 28 through conduits 36 and with header 31 through conduits 37 and some of water wall tubes 29 through conduits 38. At the lower end thereof, downcomers 34 and 34' each communicate with lower transverse headers 39 which lower headers are respectively adjacent the bottom of side walls 14 and 15. Water wall tubes 24 and water wall tubes 25, which line wall 14 and wall 15 respectively, communicate with transverse headers 40 disposed adjacent to and above headers 39. Headers 40 in turn communicate through tubes 41 with the adjacent transverse header 39. Transverse headers 39 are in communication with header 31 through a plurality of tubes 42, while header 30 and transverse headers 39 communicate with one another through a plurality of tubes 43.

As shown, chamber 11 is fired through an opening 44 in side wall 13 by a burner 45 which receives air for combustion through air conduit 46.

A low duty secondary steam generating section which is subjected to relatively low rates of heat absorption by combustion gases flowing in convection heat exchange relationship therewith is positioned rearwardly of wall 13 of the primary section and in the path of flow of gases passing from furnace chamber 11 through outlet 19 to flue 47, as will hereinafter be fully described. The secondary section comprises an upper steam and water drum 48 of smaller diameter than drum 21 and a lower water drum 49 positioned below drum 48 in spaced relationship thereto and in substantial vertical alignment therewith. Drums 48 and 49 are in communication with one another through a forward tube bank 50 and a rearward tube bank 51. The banks 50 and 51 each comprise a plurality of riser tubes, while drum 48 communicates with lower drum 49 through downcomers 48', positioned outside and closely adjacent to walls 14 and 15 respectively. The secondary section is blown-down through blow-down connection 49' which communicates with lower drum 49. The upper portions of drums 21 and 48 are in communication with one another through steam circulating tubes 52.

Feed for the secondary section is supplied by continuous blow-down from the primary section by means of a plurality of conduits 70 which are in communication at one end thereof with the lower portion of drum 21 and at the opposite end thereof with headers 71, which headers project downwardly from opposite ends of drum 48 outwardly respectively of side walls 14 and 15.

As shown, a forward superheater section 53 and a rearward superheater section 54 are positioned in the space between gas outlet 19 and tube bank 50. Rearward superheater section 54 is connected at the inlet thereof with superheater inlet header 55 by conduit 56 and at the outlet 57 thereof, which outlet is in communication with intermediate superheater header 58. Superheater section 53 is in communication at the inlet 59 thereof with intermediate header 58 and at the outlet thereof with outlet header 60. Outlet 60 has an off-take pipe 61 which supplies steam to a turbine or any other point of use, while inlet header 55 communicates with drum 21 through saturated steam outlet conduit 62. Superheater headers 55, 58 and 60 are supported from a grinder 63 by hangers 64. Superheater section 54 is positioned in a passage 65 separated from the main passage between outlet 19 and flue 47 by baffles 66 and 67. Passage 65 has superheat control dampers 68 positioned in openings 69 in the

upper part of said passage to control the flow of gases over superheating section 54.

Air passing through intake conduit 46 is heated by an air heater 12 in which gases flowing through conduit 41 and air passing through conduit 46 flow in indirect heat exchange relationship with one another.

Steam, prior to passing from the steam generator in the present invention, is treated to eliminate mechanically entrained moisture carrying dissolved chemicals, mechanically suspended fine particles of solid matter, vapors which condense as solids and compounds dissolved in the steam which have become crystallized. Such treatment is accomplished by apparatus contained in drum 21 of the primary section. As shown more particularly in Figs. 4 to 10 inclusive, the steam drum is partitioned to form steam receiving chambers adjacent the inner periphery of the drum by a partition which comprises side plates 13 and 14 spaced from the inner periphery of the drum at the opposite sides thereof and which extend longitudinally of said drum to points short of the opposite ends thereof and in laterally spaced relationship to one another. The plates 13 and 14 each have an upper portion 75 and 76 respectively which extends inwardly of the drum and are secured to the longitudinally extending bars 77 and 78 respectively by bolts 79 and 80. The bars 77 and 78 are secured to the inner periphery of the drum by welding (Fig. 7). The partition plates 13 and 14 also have inwardly inclined bottom portions 81 and 82 inclined inwardly from the peripheral surface of the drum and in spaced relationship thereto, which bottom portions are similar to the top portions 75 and 76 and are secured to longitudinally extending mounting members 83 and 84 respectively. A partition plate 85 of substantially the same length as plates 13 and 14 extends longitudinally of the drum in spaced relationship with the inner periphery thereof at the bottom, the opposite sides of plate 85 being secured to members 83 and 84 respectively.

Steam condensing chambers 86 and 87 are formed adjacent the upper part of plates 75 and 76 and between said plates and the inner periphery of drum 21 at opposite sides of the drum by metal partition members 88 and 89. The partition members 88 are secured at one end thereof to partition 75 below the inclined portion thereof and extend transversely of the drum to the inner periphery thereof and upwardly along said inner periphery to a point adjacent member 77 thereafter to project inwardly, thence upwardly and secured to the member 77 by bolt 79. The partition member 89 is similar to the partition member 88 and is secured at one end thereof to partition 76 and at the opposite end to member 78 by bolt 80. In this manner, steam condensing chambers 86 and 87 are formed, which chambers extend longitudinally of the drum adjacent opposite sides thereof so that the chambers 86 and 87 receive steam from drum 48 of the secondary section through tubes 52. These condensing chambers are open at the opposite ends thereof so that they communicate with the interior of the drum but are in fluid-tight relationship with steam receiving chambers 90 and 91, which are directly below condensing chambers 86 and 87 respectively. Steam receiving chambers 90 and 91 extend longitudinally of the drum at opposite sides thereof between partitions 13 and 14 and the inner periphery of the drum respectively. Chambers 90 and 91 are in communication with pas-

sage 92 beneath bottom plate 85. Chambers 90 and 91 are closed at the opposite ends thereof by end plates 93 and 94 respectively and the passage 92 is closed at the opposite ends thereof by end plates 95 so that steam received within said chambers and passage from the primary section will pass into a central chamber 111 of the drum only through steam treating apparatus as hereinafter described. Central chamber 111 extends longitudinally of drum 21 in the central portion thereof, and is defined along the opposite longitudinal sides thereof by a row of steam and water separating boxes 99 and a row of steam and water separating boxes 100 respectively. The bottom of chamber 111 which is defined by partition plate 85 is in communication with downcomers 32 through outlet openings 120 in plate 85. Water from chamber 111 flows downwardly through openings 120 and fluid-tight passages 121 formed of plates 122 which conduct the feed water from chamber 111 through passage 92 and out of contact with steam flowing in said passage.

Feed water for the vapor generator of the present invention is fed to drum 21 through a plurality of off-take conduits 97 and 98 extending from the opposite sides of a feed water pipe 96 disposed in central chamber 111 adjacent the bottom thereof and extending longitudinally of the chamber. The off-take conduits 97 and 98 extend from opposite sides respectively of pipe 96 and are laterally spaced from one another longitudinally of said pipe. Off-takes 97 extend transversely of the drum toward bottom portion 81 of partition 13, through said bottom portion into chamber 90 thence upwardly along partition 13 and into condensing chamber 86, thence along upper portion 75 to a point short of the top of said chamber. Off-takes 98 also extend transversely of the drum 21 toward partition 14 thence through bottom portion 82 thereof, upwardly along partition 14 into condensing chamber 87 thereafter to extend along upper portion 76 to a point short of the top of chamber 87.

A plurality of separating boxes 99 and 100 are disposed in laterally abutting relationship with one another in a row which extends longitudinally of partition plates 13 and 14. As shown in Fig. 6, the boxes comprise opposite side plates 101 and 102, a rearward plate 103 and the partitions 13 and 14 form the opposite end plate of said boxes. The separating boxes are substantially square in cross section and have a steam inlet slot 104 at one side thereof adjacent the bottom, Figs. 6 and 8 to 10, through which steam from chambers 90 and 91 enters the boxes 99 and 100 respectively. Feed water is injected into boxes 99 and 100 tangentially thereof through slots 105 and 106 which communicate with off-takes 97 and 98 respectively in order to accentuate the whirl within the boxes 99 and 100 and to effect mixing between the feed water and boiler water. The feed water is divided among the plurality of boxes 99 and the plurality of boxes 100 so that each box receives an equal share of a predetermined fraction of the total feed water. Boxes 99 and 100 have steam outlets 107 and 108 respectively at the top thereof through which steam passes into spaces 109 and 110 respectively. The spaces 109 and 110 communicate with the upper portion of chamber 111 through dryers 112 and 113, which as shown are of the chevron type. Each of these dryers comprise a plurality of laterally adjoining longitudinally extending rows each of which has a plurality of vertically extending horizon-

tally spaced V-shaped plates which are positioned in said row with the apex edge of one plate within the area bounded by the next adjacent plate in the row. The separating boxes 99 and 100 are open at the bottom thereof and in communication with the lower portion of chamber 111.

As shown in Fig. 8, the boxes 99 and 100 have a circular liner 114, while in Fig. 9 the box is of a rectangular cross section without a liner.

Feed water is projected from off-takes 97 and 98 into condensing chambers 86 and 87 respectively through outlet nozzles 115 and 116, said water impinging on hooked-shaped baffle plates 117 and 118. The baffle plates extend longitudinally of chambers 86 and 87 and are so positioned as to direct the feed water downwardly into the chambers. Water from condensing chambers 86 and 87 flows into chamber 111 from the ends of said condensing chambers.

In operation, steam is generated in the primary high duty section of the steam generator of the present invention through the circulation of water from chamber 111 in drum 21 downwardly through openings 120 in partition 85, through passage 121 into downcomer tubes 32, thence into header 33 thereafter to pass into main downcomer conduits 34 and 34'. From main downcomer conduits 34 and 34', the feed water flows into headers 30 and 31 through tubes 35 and conduits 37 respectively and from headers 30 and 31 into lower transverse header 39 through the plurality of tubes 42 and 43 and from header 39 to transverse header 40 through tubes 41. From transverse header 40, feed water enters water wall tubes 24 and 25. Water wall tubes 28 and 29 receive feed water from downcomers 34 and 34' through conduits 36 and 38 respectively and also from headers 30 and 31.

Steam is generated in the tubes 24, 25, 28 and 29 respectively by the passage of gases of combustion in chamber 11 in indirect heat exchange relationship with said tubes. The mixture of steam and water from these tubes enters chambers 90 and 91 of drum 21, said mixture from water wall tubes 28 and 29 flowing directly to chamber 90, while the steam and water mixture from tubes 24 and 25 passes into upper headers 23 thence to chamber 91 through tubes 22 and into chamber 90 through tubes 22'.

The steam and water entering chambers 90 and 91 is centrifuged and some of the steam is condensed in separating boxes 99 and 100 respectively, the steam entering the boxes through slots 104 therein. Feed water from feed water pipe 96 flows into boxes 99 and 100 through slots 104 therein, said feed water flowing from feed pipe 96 through off-takes 97 and nozzles 105 into boxes 99 and into boxes 100 through off-takes 98 and nozzles 106. Steam and water mixture from chamber 90 together with feed water from nozzles 105 flows into boxes 99 tangentially thereof while steam and water mixture from chamber 91 with feed water from nozzles 106 passes into boxes 100 tangentially thereof thereby whirling or centrifuging the mixture and the feed water. The feed water is heated to saturation by being brought into direct heat exchange relationship with the steam and water mixture and the condensation of part of the steam. Centrifuging or whirling of the steam and water mixture together with the feed water also separates the steam and the water and the entrained moisture and any entrained substance of higher specific gravity than the steam from 75 the condensing chambers through nozzles 115

said steam. The separated steam, which is of lighter specific gravity than the feed water and any entrained moisture or substance, flows upwardly from the center of boxes 99 and 100 through steam outlets 107 and 108 respectively. The separated steam from boxes 99 enters space 109 and the steam is directed by inwardly inclined portion 75 of plate 73 towards chevron dryer 112 through which the steam passes and is dried by flowing through the spaces between the plurality of plates comprising the dryer. The separated water from boxes 99 passes downwardly along inwardly inclined portion 81 of plate 73 into chamber 111 and the moisture separated from the steam in dryer 112 also flows downwardly into said chamber. The separated steam from boxes 100 flows upwardly therefrom through outlets 108 and is directed by inclined portion 76 of partition plate 74 into chevron dryer 113, while the separated water flows downwardly from boxes 100 into chamber 111. Since chambers 91 and 90 are in communication with one another through lower passage 92, the steam from one of said chambers may pass to the other chamber.

When circular liners are used in boxes 99 and 100, as shown in Figs. 4, 6 and 8, the mixture of steam and water and the feed water is guided in a circular path by the liner 114. However, when a square box is used, as shown in Fig. 9, steam free water is forced into the corners of the boxes and drained to the chamber 111 along said corners without re-entraining steam because of the increased pressure which results from the conversion of the velocity head of the whirling water into a static head in the corners. The separated steam passes to the whirling core of the mixture of feed water and steam and water and leaves the boxes through openings 107 or 108.

By treating the steam and water mixture and the feed water in boxes 99 and 100 as hereinabove described, dry steam only enters chamber 111 and heated feed water passes into said chamber thereafter to flow into downcomers 32, 34, 34' and 70.

The primary section is continuously blown-down to the secondary section through downcomers 70, the blow-down entering headers 71 which communicate with upper drum 48 of the secondary section. From drum 48 the feed water, which is highly concentrated, flows downwardly to lower drum 49 through downcomers 48'. Forward tube bank 50 and rearward tube bank 51, which comprise riser tubes, receive feed from drum 49, steam being generated in said banks by the passage of gases in convection heat exchange relationship with the tubes thereof. The gases prior to flowing over banks 50 and 51 pass through gas outlet 19 over the upper portion of tubes 29 thence in convection heat exchange relationship with superheater section 53. If superheater control dampers 68 are opened, as shown in Fig. 1, gases will pass upwardly in passage 65 over superheater section 54 thence through openings 69 thereafter to flow downwardly prior to passing over banks 50 and 51. The secondary section is blown-down through blow-down connection 49'. Steam generated in the secondary section flows from drum 48 through steam circulating tubes 52 into condensing chambers 86 and 87. Steam from tubes 52 is condensed by passing in direct heat exchange relationship with the remaining portion of the feed water flowing from off-takes 97 and 98 into 65 the condensing chambers through nozzles 115

and 116 respectively. The feed water from nozzles 115 and 116 is directed downwardly in a sheet in front of the outlets of tubes 52. Because of the high heat transfer rates through the direct contact of the feed water sheets and the steam from the secondary drum, the steam will be completely condensed and the vaporized silica or other solute contained in the steam will go back into solution in the condensate. Condensate from the chambers 86 and 87 drains downwardly into the feed water in chamber 111.

By heating the feed water to saturation through condensing steam therewith in boxes 99 and 100 prior to the entry of feed water into the downcomers, it is possible to maintain subcooling in the downcomers to a minimum. This is graphically illustrated in the upper portion of the chart shown in Fig. 11, wherein the uppermost curve of the chart illustrates the total circulation within drum 21 of the primary section, while the upper dot and dash line and the dotted line therebelow illustrate the maximum subcooling in the downcomers of the primary section and the anticipated subcooling therein respectively.

The lower portion of the chart of Fig. 11 graphically illustrates relationships between the total output of the boiler of the present invention to the steam actually generated therein, total feed to the boiler, which includes a 15% allowance for blow-down, to the feed required to condense the steam from the secondary section and the feed actually supplied to the condensing compartments, the steam generated by the secondary section and the steam required to heat all the feed to the condensing section to saturation temperature. Referring to the chart, the line A indicates the total evaporation of the steam generator of the present invention, while the dotted line B indicates steam from drum 48, while the distance between lines A and B, for example, line C, designates the steam actually generated in the steam generator. Line D indicates the total feed water fed to the boiler including 15% allowance for blow-down, while line E designates the feed to condensing chambers 86 and 87. The vertical distance between lines D and E, for example, line F, indicates the feed used in boxes 99 and 100. Line G illustrates the feed required to condense steam from drum 48, while the space between lines E and G, for example, line H, shows excess feed to condensing chambers 86 and 87. Line I shows the steam required to heat the feed water used in condensing chambers 86 and 87 to saturation, while the space between lines I and B, for example, line J, illustrates the excess steam required to heat the feed water used in the condensers to saturation.

Although the invention has been disclosed as applied to the generation of steam, it is not limited thereto but is capable of application to the generation of vapors generally.

From the foregoing, it will be perceived that by utilizing the method and apparatus of the present invention, pure steam that is, steam free of dissolved or vaporized solutes is produced and concentration of dissolved solids in the boiler water of a steam generator is controlled. Also, sub-cooling of the downcomers of steam generator embodying the present invention is prevented.

It will be understood that changes may be made in the form, location and relative arrangement of the several parts of the apparatus disclosed, and in the sequence of the steps of the method disclosed, without departing from the

principles of the invention. Accordingly, the invention is not to be limited excepting by the scope of the appended claims.

What is claimed is:

- 5 1. A steam generator having a setting with a combustion chamber therein, means for producing a stream of products of combustion for firing the apparatus, the chamber having a gas outlet opening, a primary steam generating section comprising an upper steam and water drum, downcomer tubes in communication with said drum to receive water therefrom, riser tubes in heat exchange relationship with said stream of products of combustion flowing to said outlet opening, the riser tubes being in communication with the downcomer tubes to receive water therefrom and with the said drum to discharge a mixture of steam and water thereinto, said setting having a gas outlet, a secondary steam generating section having a circulatory circuit separate from the circulatory circuit of said primary section, said secondary section being disposed in heat exchange relationship with gases of combustion flowing from said gas outlet opening to said gas outlet, conduit means connecting the water space of the steam and water drum of the primary section and the water space of the upper drum of the secondary section, steam condensing means disposed in said steam and water drum, means for conducting the steam generated in the secondary section to said condensing means, means for conducting feed water to said steam and water drum, means for passing at least a portion of said feed water to the condensing means for use as a condensing medium, means for conducting the condensing medium and the condensate from the condenser to said downcomers out of contact with the steam generated in the primary section, a usable steam off-take for receiving steam generated in said steam generator, the off-take being in communication with the steam and water drum of the primary section so as to receive said usable steam therefrom, and blowdown means for the steam generator associated with said secondary section.
- 10 2. A steam generator having a setting with a combustion chamber therein, means for producing a stream of products of combustion for firing the apparatus, the chamber having a gas outlet opening, a primary steam generating section comprising an upper steam and water drum, downcomer tubes in communication with said drum to receive water therefrom, riser tubes in heat exchange relationship with said stream of products of combustion flowing to said outlet opening, the riser tubes being in communication with the downcomer tubes to receive water therefrom and with the said drum to discharge a mixture of steam and water thereinto, said setting having a gas outlet, a secondary steam generating section having an upper drum, a lower drum positioned beneath and in spaced relationship with the secondary upper drum, downcomer tubes in communication with said secondary upper drum and with said lower drum therebeneath, a plurality of riser tubes in communication at the opposite ends thereof with said upper and lower drums respectively, said riser tubes being positioned in the path of gases of combustion flowing from said gas outlet opening to said gas outlet, steam condensing means disposed in the steam and water drum of the primary section, means for conducting the steam generated in the secondary section to said condensing means, means for conducting feed water to said primary

mary section steam and water drum, means for passing at least a portion of said feed water to the condensing means for use as a condensing medium, means for conducting the condensing medium and the condensate from the condenser to said downcomers out of contact with the steam generated in the primary section, conduit means connecting the water space of said steam and water drum of the primary section and the water space of the upper drum of the secondary section, a usable steam offtake for receiving steam generated in said steam generator, the offtake being in communication with the steam and water drum of the primary section so as to receive said usable steam therefrom, and blow-down means for the steam generator associated with the lower drum of the secondary section.

3. The steam generator of claim 2 wherein steam and water treating means is associated with said primary steam generating section, said treating means being constructed and arranged to bring steam and feed water into heat exchange relationship with one another and thereafter separate the steam and water, the treating means receiving water and steam from said primary steam generating section, the steam treating means also communicating with the steam offtake so that separated steam passes from the treating means thereto and with said primary section so that separated water passes thereto.

4. A steam generator having a setting with a combustion chamber therein, means for producing a stream of products of combustion for firing the apparatus, the chamber having a gas outlet opening, a primary steam generating section comprising an upper steam and water drum, downcomer tubes in communication with said drum to receive water therefrom, riser tubes in heat exchange relationship with said stream of products of combustion flowing to said outlet opening, the riser tubes being in communication with the downcomer tubes to receive water therefrom and with the said drum to discharge a mixture of steam and water thereto, said setting having a gas outlet, a secondary steam generating section having an upper drum, a lower drum positioned beneath and in spaced relationship with the secondary section upper drum, downcomer tubes in communication with said secondary section upper drum and with said lower drum therebeneath, a plurality of riser tubes in communication at the opposite ends thereof with said upper and lower drums respectively of the secondary section, said riser tubes being positioned in the path of gases of combustion flowing from said gas outlet opening to said gas outlet, steam condensing means in the steam and water drum of the primary section and constructed and arranged so as to completely condense steam by passage thereof in direct heat exchange relationship with water, means for conducting the steam generated in the secondary section to said condensing means, steam and water centrifuging means in the steam and water drum of the primary section, said steam and water centrifuging means being constructed and arranged to separate steam and water from a mixture thereof by centrifugal force, means for conducting feed water to said primary section steam and water drum, means for passing a portion of said feed water to said centrifuging means prior to passage thereof to the circulatory circuit of said primary section and for passing another portion of the feed water to the

condensing means for use as a condensing medium, the centrifuging means being in communication with the circulatory circuit of the primary section so as to receive the mixture of steam and water generated therein and to return separated water thereto, a usable steam offtake for receiving steam generated in said steam generator in communication with the steam and water drum of the primary section and through which separated steam from said centrifuging means is withdrawn from the primary circuit, drying means in the path of flow of the separated steam from the centrifuging means to the last-mentioned means, means for conducting the condensing medium and the condensate from the condenser to said primary section out of contact with the steam generated in the primary section, conduit means connecting the water space of the steam and water drum of the primary section and the water space of the upper drum of the secondary section, and blow-down means for the steam generator associated with the lower drum of the secondary section.

5. Steam generating apparatus comprising a plurality of separate steam generating sections, each section having a complete circulatory circuit, firing means for producing a stream of products of combustion, said apparatus having a combustion gas outlet, the sections and the gas outlet being so disposed in relationship to one another that the products of combustion flowing to the gas outlet pass in heat exchange relationship with a first of said sections prior to flowing in heat exchange relationship with another section, steam condensing means, means for supplying feed water required for all sections to said first section, means for passing at least a portion of said feed water to the condensing means for use as a condensing medium means for conducting the condensing medium and the condensate from the condenser to said first section out of contact with the steam generated in the first section, means for feeding water from the circulatory circuit of the first steam generating section to said other section, means for conducting the steam generated in the other section to said condensing means, a usable steam offtake for receiving steam generated in said steam generating apparatus, the offtake being in communication with said first section so as to receive said usable steam therefrom, and blow-down means for the steam generating apparatus associated with said other circuit.

6. Steam generating apparatus comprising a plurality of separate steam generating sections, each section having a complete circulatory circuit, firing means for producing a stream of products of combustion, said apparatus having a combustion gas outlet, the sections and the gas outlet being so disposed in relationship to one another that the products of combustion flowing to the gas outlet pass in heat exchange relationship with a first of said sections prior to flowing in heat exchange relationship with another section, steam condensing means so constructed and arranged as to completely condense steam by passage thereof in direct heat exchange relationship with water, means for supplying all feed water required for all sections to said first section, means for passing at least a portion of said feed water to the condensing means for use as a condensing medium means for conducting the condensing medium and the condensate from the condenser to said first section out of contact with the steam generated in the first section, means

for feeding water from the circulatory circuit of the first steam generating section to said other section, means for conducting steam generated in the other section to said condensing means, a usable steam offtake for receiving steam generated in said steam generating apparatus, the offtake being in communication with said first section so as to receive said usable steam therefrom, and blow-down means for the steam generating apparatus associated with said other section.

7. Steam generating apparatus comprising a plurality of separate steam generating sections, each section having a complete circulatory circuit, firing means for producing a stream of products of combustion, said apparatus having a combustion gas outlet, the sections and the gas outlet being so disposed in relationship to one another that the products of combustion flowing to the gas outlet pass in heat exchange relationship with a first of said sections prior to flowing in heat exchange relationship with another section, steam condensing means, steam and water treating means constructed and arranged to bring steam and water into heat exchange relationship and thereafter separate said steam and water, means for supplying feed water required for all sections to said first section, means for passing a portion of said feed water to said steam and water treating means prior to passage thereof to the circulatory circuit of said first section and for passing another portion of the feed water to the condensing means for use as a condensing medium, the steam treating means being in communication with the circulatory circuit of the first section so as to receive the mixture of steam and water generated therein and to return separated water thereto, means for conducting the condensing medium and the condensate from the condenser to said first section out of contact with the steam generated in the first section, means for feeding water from the circulatory circuit of the first steam generating section to said other section, means for conducting the steam generated in said other section to said condensing means, a usable steam offtake for receiving steam generated in said steam generating apparatus, the offtake being in communication with said first section so as to receive the separated steam from said treating means, and blow-down means for the steam generating apparatus associated with said other section.

8. Steam generating apparatus comprising a plurality of separate steam generating sections, each section having a complete circulatory circuit, firing means for producing a stream of products of combustion, said apparatus having a combustion gas outlet, the sections and the gas outlet being so disposed in relationship to one another that the products of combustion flowing to the gas outlet pass in heat exchange relationship with a first of said sections prior to flowing in heat exchange relationship with another section, steam condensing means, steam and water centrifuging means constructed and arranged to separate steam and water from a mixture thereof by centrifugal force, means for supplying all the feed water required for all sections to said first section, means for passing a portion of said feed water to said centrifuging means prior to passage thereof to the circulatory circuit of said first section and for passing another portion of the feed water to the condensing means for use as a condensing medium, the cen-

trifuging means being in communication with the circulatory circuit of the first section so as to receive the mixture of steam and water generated therein and to return separated water thereto, means for conducting the condensing medium and the condensate from the condenser to said first section out of contact with the steam generated in the first section, means for feeding water from the circulatory circuit of the first steam generating section to said other section, means for conducting the steam generated in the other section to said condensing means, a usable steam offtake for receiving steam generated in said steam generating apparatus, the offtake being in communication with said first section so as to receive the separated steam from said steam and water centrifuging means, and blow-down means for the steam generating apparatus associated with said other section.

9. Steam generating apparatus comprising a plurality of separate steam generating sections, each section having a complete circulatory circuit, firing means for producing a stream of products of combustion, said apparatus having a combustion gas outlet, the sections and the gas outlet being so disposed in relationship to one another that the products of combustion flowing to the gas outlet pass in heat exchange relationship with a first of said sections prior to flowing in heat exchange relationship with another section, steam condensing means so constructed and arranged that steam and water flow in direct heat exchange relationship with one another, steam and water treating means constructed and arranged to bring steam and water into heat exchange relationship and thereafter separate said steam and water, means for supplying all the feed water required for all sections to said first section, means for passing a portion of said feed water to said steam and water treating means prior to passage thereof to the circulatory circuit of said first section and for passing another portion of the feed water to the condensing means for use as a condensing medium, the steam treating means being in communication with the circulatory circuit of the first section so as to receive the mixture of steam and water generated therein and to return separated water thereto, means for conducting the condensing medium and the condensate from the condenser to said first section out of contact with the steam generated in the first section, means for feeding water from the circulatory circuit of the first steam generating section to said other section, means for conducting the steam generated in the other section to said condensing means, a usable steam offtake for receiving steam generated in said steam generating apparatus, the offtake being in communication with said first section so as to receive the separated steam from said treating means, and blow-down means for the steam generating apparatus associated with said other section.

10. The steam generator of claim 8 wherein drying means is arranged in the path of flow of the separated steam from the water and steam centrifuging means to the usable steam offtake to provide the latter with dried steam.

11. A steam generator comprising a setting having a combustion gas outlet, a plurality of steam generating sections in the setting each having a complete circulatory circuit, firing means, the firing means, the steam generating sections and gas outlet being so arranged in relationship to one another that gases of combustion flowing to the outlet pass in heat exchange with

15

one of said sections prior to flowing in heat exchange relationship with another section, means for conducting water from said one section to said other section, a steam offtake for said steam generator in communication with said one section only, blowdown means connected to a concentrated water containing portion of said other section, steam condensing means in said one section, and means for conducting the steam generated in the other section to said condensing means, said condensing means being constructed and arranged to condense all of said steam conducted thereto by said condensing means by passing it in heat exchange relationship with at least part of the feed water for the steam generator and adding the resulting condensate to the water of said one section by conducting it out of contact with the steam generated therein to a water containing portion thereof.

12. A steam generator comprising a setting having a combustion gas outlet, a primary steam generating section having a complete circulatory circuit comprising an upper steam and water drum with downcomer and riser tubes in communication therewith, the downcomer tubes communicating with the drum to receive water therefrom and the riser tubes communicating with the drum to discharge steam thereinto, a secondary steam generating section having a complete circulatory circuit separate from the primary section, firing means, the firing means, steam generating sections and gas outlet being so arranged in relationship to one another that gases of combustion flowing to the outlet pass in heat exchange relationship with the primary section prior to flowing in a heat exchange relationship with the secondary section, a steam offtake for said steam generator in communication with said primary section only, means for conducting water from the primary section to said secondary section, blowdown means connected to a concen-

trated water containing portion of said secondary section, and means comprising a heat exchanger for condensing all of the steam generated in said secondary section by passing it in heat exchange relationship with at least part of the feed water for the steam generator and adding the resulting condensate to the water of said primary section by conducting it out of contact with the steam generated therein to a water containing portion thereof.

13. The steam generator of claim 12 wherein the heat exchanger comprises a condenser disposed in the steam and water drum, said condenser being so constructed and arranged that steam and water flow in direct heat exchange relationship with one another and the steam is completely condensed.

14. The steam generator of claim 13 wherein the riser tubes are disposed in radiant heat exchange relationship with the gases of combustion and the secondary section comprises an economizer disposed in convection heat exchange relationship with said gases of combustion.

MARTIN FRISCH.
